UNITED STATES PATENT OFFICE.

EMIL GRUENFELDT, OF CLEVELAND, OHIO, ASSIGNOR TO THE BAKER MOTOR VEHICLE COMPANY, OF CLEVELAND, OHIO, A CORPORATION OF OHIO.

DESIGN FOR AN AUTOMOBILE-BODY.

40,681.

Specification for Design.

Patented May 3, 1910.

Application filed February 1, 1910. Serial No. 541,404. Term of patent 7 years.

To all whom it may concern:

Be it known that I, EMIL GRUENFELDT, a subject of the Emperor of Germany, residing at Cleveland, in the county of Cuyahoga and State of Ohio, have invented a new, original, and ornamental Design for an Automobile-Body, of which the following is a specification, reference being had to the accompanying drawing, forming part thereof.

Figure 1 is a side elevation of an automo-

bile body showing my new design. Fig. 2 is a front elevation of the automobile body.

I claim:

The ornamental design for an automobile body, as shown.

EMIL GRUENFELDT.
